[57] **CLAIM**

The ornamental design for a side element of a shoe upper, as
shown and described.

DESCRIPTION

FIG. 1 is a side elevational view of a side element of a shoe
upper showing my new design;

FIG. 2 is a front elevational view thereof;

FIG. 3 is a rear elevational view thereof; and,

FIG. 4 is a top plan view thereof.

The broken line showing of a shoe and the remaining portion
of the upper shown in FIGS. 1-4 is for illustrative purposes
only and forms no part of the claimed design.
